Franklin Doane,

UNITED STATES PATENT OFFICE.

LEWIS B. DOANE, OF NEW LONDON, CONNECTICUT, ASSIGNOR TO ELECTRIC BOAT COMPANY, A CORPORATION OF NEW JERSEY.

SUBMARINE VESSEL.

1,363,851.

Specification of Letters Patent. Patented Dec. 28, 1920.

Application filed January 24, 1920. Serial No. 353,756.

To all whom it may concern:

Be it known that I, LEWIS B. DOANE, a citizen of the United States, residing at 549 Ocean avenue, New London, in the county of New London, State of Connecticut, have invented certain new and useful Improvements in Submarine Vessels; and I do hereby declare the following to be a full, clear, and exact description of the invention, such as will enable others skilled in the art to which it appertains to make and use the same.

This invention relates to submarine boats and more particularly to the mechanism employed for the propulsion of such boats.

Submarine boats as commonly constructed consist of a hull which is more or less circular in cross-section and a non-watertight superstructure erected upon this hull. The propulsion mechanism usually consists of an internal combustion engine for propelling the boat upon the surface and an electric motor supplied with current from a storage battery for propelling the boat when submerged. The present invention involves a construction of this character and relates particularly to the devices through which the exhaust from the internal combustion engine is carried to the exterior of the hull. Provision must be made for the free exhaust of the products of combustion from the engine to the exterior atmosphere when the boat is running on the surface and the passage for these exhaust products must be effectually sealed when the boat is submerged since otherwise the water of submergence would pass into the engine.

As is well recognized, it is of the utmost importance that the time required for changing a submarine from the surface-running condition to the submerged condition be reduced to a minimum. This makes it of great importance that the means for closing the passage for the exhaust products be capable of operation quickly. Furthermore, when a valve is employed for closing the exhaust passage, this valve should be provided with a relatively soft gasket to insure a watertight seal and this requires that the valve be moved against the seat with considerable pressure. When this valve with its soft gasket is in the open position it should be protected against injury by the hot products of combustion and the carbon carried thereby.

This invention is directed to the provision

of a means for closing such an exhaust outlet which fulfills all of these desirable characteristics.

In accordance with the invention, the closure for the exhaust outlet consists of a valve which is movable to a closed position and to an open position and in its open position it is submerged in a tank of water to protect the gasket of the valve. For moving the valve from this open position to the closed position two mechanisms are provided, one of which is capable of moving the valve rapidly from its open position to substantially the closed position, and the other operating mechanism is adapted for moving the valve slowly and exerting considerable power to move it so that the gasket of the valve will be compressed enough to insure a watertight closure. This second operating mechanism for moving the valve preferably includes a worm and worm-gear as such gearing constitutes a lock for holding the valve against unintended retractile movement. In combination with these parts, a cover is preferably provided movable in correspondence with the movement of the valve and so positioned that when the valve is in its open position the cover serves as a shield to protect the valve from contact with the hot products of combustion.

The preferred embodiment of the invention is illustrated in the accompanying drawings in which Figure 1 is a diagrammatic view in elevation of the stern of a submarine boat; and Fig. 2 is a longitudinal section through a portion of the superstructure of the boat on an enlarged scale.

Referring to these drawings, 3 indicates the watertight hull of a submarine boat. It is more or less circular in cross-section. On this is erected a superstructure 4 which is not watertight. Within the hull of the boat is an internal combustion engine 5 for driving the propeller 6. Also, an electric motor 7 is provided and the arrangement is such that either the engine 5 or the motor 7 may be connected to the shaft 8 of the propeller 6 at will, the engine being used for surface running and the motor for submerged running. The exhaust from the engine 5 is normally led to and through a pipe 9 to a muffler 10 mounted within the superstructure 4. These exhaust devices will now be described in connection with Fig. 2.

The exhaust pipe 9 passes through an

opening in the hull of the boat and is connected to one end of an L 11 within the superstructure. The opposite end this L is connected to a valve casing 12 and this 5 casing communicates with the muffler 10. Preferably both the L 11 and the valve-casing 12 are water-jacketed, and the valve-casing 12 may, if desired, be provided with a movable wall constituting a valve which 10 may be opened to permit the exhaust products to escape without passing through the muffler 10. The end of the L 11 within the valve-casing 12 constitutes a seat for a valve 14 by which the passage for the exhaust 15 gases from the engine to the muffler is closed. This valve is provided with a gasket of rubber or other similar material set in a groove in the face of the valve and adapted to be pressed against the seat of the valve 20 when the valve is moved to the closed position. The valve is carried by an arm 15 which is pivotally mounted by being secured to a shaft 16 journaled in a frame 17 mounted upon the hull of a boat. Preferably the shaft 16 has a counterweight 18 mounted thereon to balance the weight of the valve and its supporting arm. A tank 19 is mounted upon the hull of the boat in such position that when the valve 14 is 25 moved to the open position by turning shaft 16, the valve will be carried down into the water within the tank 19. In so moving from the closed to the open position, the valve 14 passes through a circular opening 30 in the bottom wall of the valve casing 12. The bounding wall of this circular opening forms a seat for a cover 20 of circular form. This cover is carried by an arm 21 which is pivotally mounted by being supported on 35 a shaft 22 journaled in bearings carried by the valve casing 12. The shaft 22 carries a crank arm 23 and the shaft 16 carries a similar crank arm 24. These two crank arms are connected by a link 25 so that the 40 shafts 16 and 22 move together. Fig. 2 shows three positions of the valve 14 and the cover 20. When the valve 14 is in the closed position the cover is in the intermediate one of its three positions in which it 45 is shown in dotted lines. During the first portion of the opening movement of the valve 14, the cover is moved about the shaft 22 in a counter-clockwise direction until it reaches the position in which it is shown 50 in the dot and dash lines. Thereafter the opening movement of valve 14 continues until the valve reaches the full open position and is submerged within the tank 19 and during this movement of the valve the 55 cover 20 is moved in a clockwise direction until it is brought down upon the seat provided for it on the bottom wall of the casing 12. Thus when the valve 14 is in the open 60 position it is submerged in water which protects it and particularly protects its gasket 65

from injury from the hot products of combustion. Furthermore, the opening through which the valve passes in moving from its closed to its open position is closed after the passage of the valve therethrough by the 70 cover 20 which affords further protection for the valve and its gasket from the products of combustion.

The valve 14 and cover 20 are moved to their open and closed positions from within 75 the hull of the boat. For this purpose, two actuating mechanisms are provided, both operating through a vertical shaft 26 which passes through an opening in the hull of the boat and a suitable stuffing box for preventing leakage through that opening. At its upper end the shaft 26 carries a bevel gear 27 which meshes with a bevel gear 28 on the shaft 16. At its lower end the shaft 26 carries a bevel gear 29 which meshes with a 80 similar gear 30 on a horizontal shaft 31 which is journaled in bearings carried by a frame 32 depending from the roof of the hull 3. Fixed upon the shaft 31 is a hand lever 33 provided with a latch 34 coacting with notches on a stationarily mounted sector 35.

Secured to the shaft 31 is an arm 36 and loosely mounted upon the shaft 31 beside this arm 36 is a worm wheel 37. This worm 95 wheel has a recess in one of its faces and the arm 36 lies within this recess. The wheel 37 is provided with a lug 40 which lies in the path of movement of the end of the arm 36. The worm wheel 36 meshes with 100 a worm 41 on a short shaft which carries a hand wheel 42.

The operation of these parts of the mechanism will now be described. When the valve 14 is in the closed position, the hand 105 lever 33 is in its lower position and the lever is raised to open the valve and lowered to close it. Assume that the valve is in the open position and the lever 33 is in the upper position, that the boat is being propelled by 110 the engine upon the surface and that it is desired to submerge. The steps incident to submergence must be performed quickly so that the boat will be submerged in the minimum of time. One of the necessary steps 115 incident to submerging the boat is to close the exhaust passage to prevent water of submergence from flowing into the engine. To do this the operator grasps the lever 33 and moves it downwardly. This turns shaft 31 120 and operates through the gears 30, 29, 27 and 28 to rotate the shaft 16 which carries the valve 14. Also, the rotation of shaft 16 operates through the link 25 and its co-operating crank arms to turn the shaft 22. The 125 arrangement of the parts is such that this rotation of the shafts 16 and 22 operates to raise the cover 20 from its seat out of the path of movement of the valve 14, move the valve through the opening provided by rais- 130

ing cover 20 and into contact with its seat and then retract the cover 20 somewhat. As the lever 33 is moved downward thus, the arm 36 carried by the shaft 31 is moved back 5 away from the lug 40. The operator then grasps the hand wheel 42 and turns it, thus operating through the worm 41 to rotate worm wheel 37 until the lug 40 is carried around again into contact with the end of 10 arm 36. When this contact of the lug and the end of the arm has been re-established, the rotation of the hand wheel 42 is continued with the result that the shaft 31 is turned on a little farther in its bearings and 15 this turning movement operates through the gearing connected to shaft 31 to force the valve 14 tightly against its seat, compressing the gasket carried by the valve and effecting a watertight seal at the end of the 20 L 11.

In this condition of the parts, the valve 14 is locked against any retractile movement by the worm wheel 37 and worm 41. In opening the exhaust passage, speed is not 25 of such consequence. The hand wheel 42 is turned to move the lug 40 around a substantial distance and the hand lever 33 is raised, thus actuating the valve 14 and cover 20 as hereinbefore described.

30 It will be noted that the hand lever 33 and the hand wheel 42 constitute two operating devices for effecting the movement of the valve which controls the exhaust passage. The handle 33 may be moved quickly 35 and it is so connected to the valve 14 that it moves that valve quickly from the full-open to the closed position. The hand wheel 42 is so geared to the valve that it moves it slowly through worm gearing and may be 40 manipulated readily to force the valve against its seat with the pressure required for effecting a watertight joint. In the closed position the valve is held effectively against any retractile movement by the 45 worm gearing and in the open position it and its gasket are amply protected against injury by the water in the tank 19 and by the cover 20.

I claim:

- 50 1. A submarine boat having a hull, an internal combustion engine therein, an exhaust passage for the engine leading outside the hull, an opening in the side of the passage, a closure arranged to be moved through the 55 opening to close the exhaust passage, a cover for the opening adapted to close it when the closure is withdrawn, and operating mechanism operated from within the hull for moving said closure and cover.
- 60 2. A submarine boat having a hull, an internal combustion engine therein, an exhaust outlet for the engine leading outside the hull, a closure for said outlet located outside the hull and two operating mechanisms for said closure, one for positively 65

moving the closure rapidly to its seat and the other for moving it slowly to carry it tightly against its seat.

3. A submarine boat having a hull, an internal combustion engine therein, an exhaust outlet for the engine leading outside the hull, a closure for said outlet located outside the hull and two operating mechanisms for said closure located within the hull of the boat, one of said mechanisms being adapted positively to move the closure rapidly to its seat and the other for moving it slowly to carry it tightly against its seat. 70 75

4. A submarine boat having a hull, an internal combustion engine therein, an exhaust outlet for the engine leading outside the hull, a closure for said outlet located outside the hull and two operating mechanisms for said closure, one of which is adapted positively to move it rapidly to its seat 80 and the other of which includes worm gearing and is adapted to move the closure slowly to carry it tightly against its seat and lock it in that position.

5. A submarine boat having a hull, an internal combustion engine therein, an exhaust outlet for the engine leading outside the hull, a closure for said outlet located outside the hull and two operating mechanisms for said closure, one for positively moving 90 the closure rapidly to its seat and the other for moving it slowly to carry it tightly against its seat, the latter of said mechanisms being connected loosely to the closure so that it may be brought into operation after the closure has been moved to its seat by the other mechanisms. 95 100

6. A submarine boat having a hull, an internal combustion engine therein, an exhaust outlet for the engine leading outside the 105 hull, a closure for said outlet, means for moving the closure to its closing position and to an open position and a tank into which the closure is carried when it is moved to its open position. 110

7. A submarine boat having a hull, a superstructure thereon, an internal combustion engine within the hull, an exhaust outlet for the engine leading into the superstructure, a valve in the superstructure for 115 closing said outlet, mechanism operable from within the hull for moving the valve to its closing position and to an open position and a tank within the superstructure into which the valve is carried when it is moved to its open position. 120

8. A submarine boat having a hull, an internal combustion engine therein, an exhaust outlet for the engine leading outside the hull, a closure for said outlet, means for 125 moving said closure to its closing position and to an open position and a shield connected to said means and movable thereby, simultaneously with the movement of the closure to its open position, into a position 130

for shielding the closure from exhaust products passing through the exhaust outlet.

9. A submarine boat having a hull, a superstructure thereon, an internal combustion engine within the hull, an exhaust outlet for the engine leading into the superstructure, a valve in the superstructure for closing the exhaust outlet, mechanism operated from within the hull for moving the valve to its closing and to an open position and a shield within the superstructure connected to said mechanism and moved by the mechanism when moving the valve to its open position into a position for shielding the valve from contact with the products of combustion passing through the exhaust outlet.

10. A submarine boat having a hull, a

superstructure thereon, an internal combustion engine within the hull, an exhaust outlet extending from the engine into the superstructure, a muffler in the superstructure, a casing connecting the exhaust outlet to the muffler and having an opening therein, a valve for the exhaust outlet located within the superstructure, an operating mechanism operable from within the hull for moving the valve from its closing position through the opening in said casing to an open position and a cover connected to said mechanism and moved thereby to close said opening in the casing after the valve has been moved through that opening to its open position.

In testimony whereof I affix my signature.

LEWIS B. DOANE.
